UNITED STATES PATENT OFFICE.

CLEMENT A. ROSSBACH, OF MILWAUKEE, WISCONSIN, ASSIGNOR, BY MESNE ASSIGNMENTS, TO THE FISK RUBBER COMPANY, OF CHICOPEE FALLS, MASSACHUSETTS, A CORPORATION OF MASSACHUSETTS.

CALENDERING.

Application filed October 27, 1921. Serial No. 510,786.

To all whom it may concern:

Be it known that I, CLEMENT A. ROSSBACH, a citizen of the United States, and a resident of Milwaukee, in the county of Milwaukee and State of Wisconsin, have invented certain new and useful Improvements in Calendering, of which the following is a specification.

My invention relates to calendering and the principal object of my invention is to provide new and improved means for supplying stock to a calender. In the drawings accompanying this specification and forming a part thereof I have shown, for purposes of illustration, one form which my invention may assume.

In these drawings:

Figure 1 represents a general view of this illustrative embodiment, while Figures 2 and 3 are respectively a plan view and a side elevation of the stock-cutting mechanism shown in Figure 1.

The device herein shown comprises a warming mill 11, a stock-cutting mechanism 12, a conveyor 13, a distributor 14, and a calender 15. The warming mill 11 and the calender 15 may be of the type now commonly in use.

The stock-cutting mechanism 12 comprises a pair of knives 16 secured to a block 17 which in turn is slidably mounted on a shaft 18 which may be fixed to the warming-mill frame. The block 17 is provided with a pin 19 adapted to ride in the groove 20 of a cam 21 which is pivoted at 22 to any suitable support and driven by means of a chain 23 acting on a sprocket 24 and itself driven by a sprocket 25 secured to a shaft 26 on which is mounted a bevel gear 27 which meshes with the bevel gear 28 mounted on the end of the warming-mill roll 29. It is apparent from the above description that rotation of the warming mill 29 will rotate the cam 21 to thus move the knives 16 back and forth along the roll 29, as shown in dotted lines in Figure 2, to thereby cause the knives to cut a continuous strip 30 from the roll.

The strip 30 now passes to the conveyor 13. This conveyor consists of an endless belt 31 adapted to carry the strip 30, a cooperating endless belt 32 adapted to press the strip 30 into firm engagement with the

belt 31, and a transversely moving belt 33 adapted to receive the strip from the belt 31 and to deliver it to the distributor 14.

The distributor 14 comprises a framework 34 carrying a plurality of pairs of rollers 35 between which the strip 30 is adapted to pass. This frame 34 is pivotally mounted 60 at its upper end 36 and is oscillated longitudinally of the calender rolls by means of an arm 37 eccentrically connected to a disk 38 driven by means of a belt 39 passing around a pulley 40 secured to the disk and a drum 41 secured to a calender-roll shaft. It will be understood from the above that the strip 30 passes down between the pairs of pulleys 35 onto the calender roll and is then uniformly distributed by means of the oscillation of the framework 34 and the pulleys 35.

It will be understood by those skilled in the art that the thickness of the coating on the roll of the warming mill is practically constant for any given setting of the mill and accordingly it will be understood that the cutting device 12 will cut from this roll a strip of practically constant cross section which will be fed by the conveyor 13 at practically constant speed and uniformly distributed over the rolls of the calender 15 by the distributor 14. In starting or at any time when the feed is not sufficiently rapid the relative rate of feed may be increased by operating the warming mill 11, the cutting mechanism 12, and the conveyor 13 faster than the calender is operated while in closing down or in case too much stock is being fed the warming mill, the cutting mechanism, and the conveyor may be slowed down or stopped or in some cases the knives 16 may be merely lifted from the mill roll and the conveyor 13 stopped.

I have described herein one embodiment which my invention may assume but this description is of course illustrative only and my invention is not limited thereto.

I claim:

1. In combination, a warming mill, a calender, means to spirally cut stock from said mill, and means to convey said stock to said calender.

2. In combination a warming mill, a calender, cutting means movable across the face of the mill roll to cut the stock thereon

into a continuous strip, and means to convey said stock to said calender.

3. In combination a warming mill, a calender, means for conveying material from said warming mill to said calender and means for distributing said stock along the calender roll.

4. In combination a warming mill, a

calender, means to cut material on the mill, means for conveying the cut material from the warming mill to the calender and means for distributing the material along the calender roll. 10

In testimony whereof I have signed my name to the above specification.

CLEMENT A. ROSSBACH.
